UNITED STATES PATENT OFFICE.

JAMES H. GARDNER, OF BOSTON, MASSACHUSETTS.

DESIGN FOR A PRINTED FABRIC.

Application filed May 31, 1928. Serial No. 26,937. Term of patent 3½ years.

To all whom it may concern:

Be it known that I, JAMES H. GARDNER, a citizen of the United States, and a resident of the city of Boston, Massachusetts, have invented a new, original, and ornamental Design for a Printed Fabric, reference being had to the accompanying drawing, forming part thereof.

The figure represents a plan view of one repeat of my design as applied to a printed

fabric, the theme of the design being a vivification of kitchen utensils as well as a grotesque representation of domestic servants.

I claim and desire to secure by Letters Patent:

The ornamental design for a printed fabric as shown and described.

JAMES H. GARDNER.
